ZIPPER OPERATOR

Donald A. Reifsteck, Richard L. Reifsteck, and Donald E. Reifsteck, all of P.O. Box 71, Hanover, Ill.
Filed June 27, 1963, Ser. No. 292,199
1 Claim. (Cl. 24—205.15)

The present invention relates generally to operators for slide fasteners of the type generally referred to as zippers and particularly to operators constructed and arranged to prevent the zipper from catching onto the cloth of undergarments underlying zipper.

The object and general nature of this invention is the provision of a zipper operator particularly adapted to close the zipper at the back of a woman's dress, where the zipper usually extends from the waist up to the neck. More specifically, it is a feature of this invention to provide a zipper operator that readily permits one to close the zipper on her own dress, even to move the zipper all the way from the waist up to the upper portion of the dress at the neck, without requiring the assistance of another person.

Preferably, according to this invention, the zipper operator includes an elongated shield or guard that is adapted to be placed between the zipper and the adjacent undergarment and to extend upwardly far enough to permit the user to reach and engage the upper end thereof by reaching over her shoulder. Another feature of this invention resides in the connection of the zipper-engaging part by means of a relatively long flexible element so that the zipper-engaging part, which may be a hook or the like, may be readily engaged with the zipper by the user reaching around back of her waist while the upper end of the shield extends upwardly far enough to permit the user to grasp the shield by reaching back over her shoulder.

These and other objects and advantages of this invention will be apparent to those skilled in the art after a consideration of the following detailed description of the preferred embodiment, taken in conjunction with the accompanying drawings illustrating said embodiment.

In the drawings:

FIG. 1 is a perspective view showing the device of the present invention in use.

FIG. 2 is an elevational view showing the device of our invention disassociated from the dress of the user.

Our new and improved zipper operator consists of an elongated shield 1 formed of any suitable pliable plastic and comprising a strip or sheet about 24 inches long, four inches wide and of sufficient thickness that the shield is self-supported but quite flexible so that it may readily be inserted between the wearer's dress and the associated undergarment. The ends of the shield 1 are rounded and at the upper end (FIG. 2) there is a thumb hole 3. The length of the shield 1 is chosen to be about two or three inches longer than the standard dress zipper, which usually is twenty two inches.

A conventional zipper includes a slide 5 having a pivoted pull tab 6 having an opening 7. Our zipper operator is provided with a tab-engaging member, such as a hook 8, carried at the lower end of a nylon cord or other suitable strand, shown at 9. The other end of the cord 9 is fastened in any suitable way to the upper portion of the shield 1, such as adjacent the thumb hole 3. Thus, the cord is almost as long as the length of

2

the shield itself. A swivel 10 may be provided between the hook 8 and the lower end of the cord 9, if desired. The upper end of the cord 9 may be secured to the shield by providing a pair of openings in the shield, as indicated at 12, and tying the cord to the shield. Other suitable means may be used.

In using the zipper operator of this invention, before putting on her dress the user inserts the hook 8 in the opening in the zipper tab 6 and then puts on the dress. Next the user inserts the lower portion of the shield 10 in place between the zipper and the undergarment, far enough that the shield remains in an upright position with the upper end adjacent the upper part of the dress. This is possible because the cord 9 extends almost the entire length of the shield. The user then with one hand straightens the material and grasps the dress below the zipper and then with the other hand reaches back over her shoulder and inserts the thumb of the other hand into the thumb hole 3. Then, while with the one hand she holds the dress down the user pulls slowly upwardly on the shield which acts through the cord to pull the zipper up into its closed position. The user then disengages the hook 8 from the zipper, thus releasing the zipper operator.

Having described our invention, what we claim and desire to secure by Letters Patent is:

A zipper operator for a woman's dress having at the back a zipper extending generally from the waist to the neck of the wearer, said operator comprising: 30 a flattened semi-flexible self-supporting elongated member having a lower end portion and an upper end portion, the lower end portion being adapted to be inserted between the waist portion of the dress and the body of the user, the elongated member being of such length that when 35 the lower portion is disposed between the waist portion of the dress and the waist of the user that the upper portion of the elongated member is adjacent the neck of the user, a flexible hook carrying element having a zipper tab engaging hook at the lower end thereof, the upper 40 end of said flexible hook carrying element being secured to the upper end portion of the elongated member, the hook and flexible element being of such a relative length to the flattened elongated member that the hook is disposed over the lower end portion of the elongated member, and a finger receiving aperture in the upper end portion between the upper end of the flexible hook carrying element and the upper end of the elongated member, the parts being so arranged and constructed that the elongated member may be grasped when the lower portion 45 is disposed between the waist of the dress and the waist of the user by the user reaching back over her shoulder with either hand and engaging the aperture with a finger whereby the zipper tab may be pulled up.
